UNITED STATES PATENT OFFICE

WALTER J. KROLMAN, OF FLUSHING, NEW YORK

LIFEBOAT

Application filed September 27, 1929. Serial No. 395,485.

This invention relates to improvements in life boats.

One of the objects of this invention is to provide a stabilizing fender element which 5 may be applied to life boats generally in which the metallic shell is curved or arched and to provide for such boats increased protection against impact of the same in the event of collision thereof with the side of the 10 vessel.

Still another object of my invention is to produce a life boat of the folding type comprising a rigid metallic body or shell portion having sides of normal curvature and a 15 foldable superstructure or bulwarks, combined with stabilizing fender elements having such configuration or shape as to provide increased protection to the shell against impact in case of collision with the vessel.

Another object of my invention is to enable the use in combination with boats having the shell plating at opposite sides curved longitudinally and vertically so as to develop 20 the full strength of the metallic body of stabilizing fender elements which will not only provide still further increased strength and increased buoyancy but will provide a firm and secure mounting or support for the fender so as to avoid all danger of shifting or 25 slipping of the fender in relation to the shell and will also provide such an increased impact area or surface in the event of collision with the side of the vessel that greatly increased protection to the shell of the boat is 30 afforded.

Another object of my invention is to produce a life boat having a metallic shell or body provided with sides rounded vertically and longitudinally in a normally curved configuration to develop the full strength of said 35 shell in combination with stabilizing fender elements having such conformation and being so mounted on such sides as to provide elongated flat impact surfaces preferably extending 40 throughout the amidship section on opposite sides of the shell, thus providing increased strength and increased protection for the shell in that such increased surface or area of the stabilizing fender element will, 45 in the event of a bumping or collision of the

boat against the vessel during launching or hoisting, contact with the side of the vessel and afford greatly increased protection there- 55 to over fenders which are exteriorly rounded and thus present relatively small or short contact area in the event of collision.

Still another object of my invention is to provide foldable bulwarks for a boat of the type specified which will be simple, easy to manipulate and durable and which will necess- 60 itate manual manipulation so as to avoid reliance on automatic locking and thus to insure a positive locking of the foldable bulwarks in vertical position.

With these and other objects in view, the 65 invention comprises the combination of mem- bers and arrangement of parts so combined as to co-act and cooperate with each other in the performance of the functions and the accomplishment of the results herein con- 70 templated and comprises in one of its adapta- tions the species or preferred form illustrated in the accompanying drawings, in which:

Fig. 1 is a plan view of a boat embodying 75 my invention;

Fig. 2 is a view, partly in side elevation and partly in section on the line 2—2 of Fig. 1, looking in the direction of the arrow;

Fig. 3 is a cross-section on the line 3—3 of Fig. 1, looking in the direction of the arrow; 80

Fig. 4 is a fragmentary section of a fold- able bulwark and the locking brace therefor;

Fig. 5 is a plan view of a standard life boat to which my improved fender is applied;

Fig. 6 is a view, partly in side elevation 85 and partly in section, on the line 6—6 of Fig. 5, looking in the direction of the arrow; and

Fig. 7 is a cross-section on the line 7—7 of Fig. 5, looking in the direction of the arrow.

Referring now to these drawings, Figs. 1 to 4 illustrate a preferred embodiment of my invention as applied to a life boat of the foldable bulwark type and Figs. 4 to 7 inclusive show my stabilizing fender elements applied to a standard life boat. 95

In the preferred embodiment of my invention shown in Figs. 1 to 4, 1 indicates a life boat of the foldable-bulwark type comprising a metallic shell 2 preferably provided fore and aft with rounded ends 2' and 2" and 100

a flat bottom 3. In accordance with my invention, the sides 4 of this type of boat are, at the amidship section of the boat, normally rounded, curved or arched to develop the full strength of the sides of the shell, the longitudinal curve of the sides being indicated by the dotted lines 2^c in Fig. 1 and the vertical curve being shown at 2^d in Fig. 3, and these sides merge with the flat bottom 3 by means 10 of curvilinear corners 5.

By my invention, though the rounded or arched sides 4 of the shell at the amidship section of the boat are in a normal or conventional curve or arch, these curved or 15 arched sides are not, as in the conventional boat, employed as the exterior surface of the boat to round out the contour and symmetry thereof but are so rounded and arched, first, to develop the full strength of the shell and, 20 secondly, to provide an arched interior mounting for my stabilizing fender elements 16 which are mounted on such sides and are of such configuration as to provide on each side of the amidship section of the completed boat an elongated flat surface 16^a which preferably extends the major portion of the length of the fender and covers substantially the entire amidship section of the boat. I thus provide an impact surface on the fender 25 of greatly increased area which, in case the boat should collide with the side of the vessel during the launching or hoisting operations, would come into contact with the side of the vessel and being of such increased area will 30 afford increased resistance, first, to the crushing of the material of the fender and, secondly, to the crushing of the shell. This elongated flat surface preferably merges at 35 opposite ends with inwardly and upwardly inclined fore and aft fender sections which 40 terminate at pointed end sections adjacent to the gunwale.

In said preferred embodiment, each stabilizing fender element 16 is composed of a highly buoyant material such as balsa wood and has an interior countersunk surface 16' having a configuration conforming with the curvature of the side of the boat to which it is attached so that when the countersunk surface 45 of the fender is mounted on the exteriorly-curved side, a firm and non-shifting support and mounting will be provided. As illustrated, these fenders 16 are fastened to the sides of the shell by a series of straps 17 hinged at 18 to the shell plating and fastened by bolts 19 and straps 19' to the ends 20 of the thwarts 10. The boat, as illustrated, is 50 also provided with the conventional manhole 21 to permit examination and repair of the air compartments and has conventional valved, bailing tubes or scuppers 22.

In the preferred embodiment of my invention shown, the shell is divided into a series of water-tight compartments 6 formed by a 55 series of bulk-heads 7, the amidship compart-

ments being reduced in height to provide a water-tight deck 8 which is supported at the upper ends of the amidship bulk-heads and is preferably disposed, as shown, about midway of the depth of the shell between the bottom 3 and the gunwale or upper edges 2' of the shell, thus providing a deck space or loading compartment 8' in the shell above said deck 8. The shell 2 is, at its gunwale or upper edges, provided, as shown, with longitudinal seats or benches 9 and cross-seats or thwarts 10. The said upper edge or gunwale of the shell at 2' is reinforced in any suitable manner and, as illustrated, is provided with metallic reinforcing angle-irons 2^e which are 60 riveted to the top of the shell plating. The benches 9 and thwarts 10 are supported on the edges 2' and also tend to reinforce the same.

Mounted on the shell in any suitable manner and, as shown, hinged to the thwarts 10, I provide foldable side and end bulwarks 13 which fold inwardly and are capable of being swung into vertical position and manually locked in such position by a series of brace 65 members 14 pivoted at their lower ends at 14' and each having contiguous to its outer free end 14^a a keying slot and notch 14^b which is engageable over a pin 15' extending between the flanges of a channelled bracket 15.

The brace member with its keying slot and notch 14^b are so arranged relatively to the bracket 15 that by manual pressure the keying slot and notch brace may be "sprung" or forced into a locking engagement with the pin of the bracket and the slight forcing movement of the bulwarks and brace will serve to lock the brace securely to the bracket and thus to lock the bulwarks in raised position. Manual operation of the brace members, however, is necessary and is desirable to procure a positive latching or locking of the foldable bulwarks in raised position as any device which relies on an automatic locking by a mere raising of the bulwarks will be less positive than a means which requires an engaging movement of the brace member which is separate and distinct from the movement of the bulwarks themselves.

As shown, the bulwarks 13 are reinforced by cleats 13', 13^a. These cleats 13', 13^a are arranged not only to reinforce the bulwarks but to furnish a firmer support for such bulwarks on the benches and thwarts when said bulwarks are folded and thus to provide a 110 flat supporting surface for a similar boat above the same.

Referring now to Figs. 5 to 7 inclusive, 115 indicates the shell of a life boat of standard or conventional design having rounded ends 30' 30^a and an amidship section which is rounded longitudinally as shown in dotted lines at 30^b (Fig. 5) and is also rounded vertically as shown at 30^c (Fig. 7). The shell 30 is, as illustrated, provided with a gunwale 120

31 which has, at the amidship section of the boat, the conventional rectilinear portions 31'. In the standard life boat, the rectilinear section has a molding which is extended outwardly to cover the bulged portion so that this overhanging gunwale molding will receive and resist any blow due to collision of the life boat with the side of the vessel during launching thereof.

10 In accordance with my present invention, I apply below the rectilinear gunwale portion 31' stabilizing fender elements 32 which are attached to the shell plating in a manner substantially similar to the construction hereinabove described in relation to Figs. 1 to 4. These fenders are substantially similar in construction to the fender stabilizing elements 16 hereinabove described in relation to Figs. 1 to 4 and in particular have the 15 curved interior surfaces 32^a conforming in configuration to the shape of the shell plating and also having flat outer surfaces 32' extending substantially throughout the amidship section of the boat and adapted, in 20 the event of a collision during the hoisting and lowering of the boat, to contact with the side of the vessel and to receive and resist any blow or impact resulting therefrom. In view of the application of fenders of this 25 type, the usual overhanging gunwale molding may be omitted in this type of boat as the stabilizing fender elements, when applied to a boat of this type, will protect the sheet metal shell in a much more efficient manner 30 than the aforesaid overhanging gunwale molding.

In other respects, the boat shown in Figs. 5 to 7 is of the conventional standard construction and need not be further described.

40 Having described my invention, I claim:—
1. A life boat embodying, in combination, a metallic shell having its opposite side walls normally curved at the amidship section of the boat, stabilizing fender elements composed of highly buoyant material and having inner surfaces substantially conforming with the curvatures of said side walls and secured thereon, said elements being provided with outer rectilinear flat impact surfaces extending in substantially the same vertical plane over a substantial area along the amidship section of the boat, and having walls varying in thickness to compensate for the space between said rectilinear impact surfaces and the 45 curved sides of the boat.

50 2. A life boat embodying, in combination, a metallic shell having its opposite side walls normally curved at the amidship section of the boat, stabilizing fender elements composed of highly buoyant material and having inner surfaces substantially conforming with the curvatures of said side walls and secured thereon, said elements being provided with outer rectilinear flat impact surfaces extending in substantially the same vertical plane

55 the major portion of the length of the fender and a major portion of the length of the boat, the walls of said elements varying in thickness to compensate for the space between said rectilinear impact surfaces and the curved sides of the boat.

60 3. A life boat embodying, in combination, a metallic shell having its opposite side walls normally curved at the amidship section of the boat, stabilizing fender elements composed of highly buoyant material and having inner surfaces substantially conforming with the curvatures of said side walls and secured thereon, said elements being provided with outer rectilinear flat impact surfaces extending in the major portion of the length of the fender and a major portion of the length of the boat, said fender having terminal surface portions inclining from said flat surface in rectilinear lines inwardly and upwardly to the gunwale of the shell at the forward and rear ends thereof.

65 In witness whereof, I have signed my name to the foregoing specification.

70 WALTER J. KROLMAN.
